(57) **ABSTRACT**

A torque fluctuation absorber includes a first outer helical spline, an intermediate member, an outer member, a first spring, and a second spring. The first outer helical spline is rotatable integrally with a torque transmission shaft. The intermediate member is able to move in a first axial direction and in a second axial direction. The intermediate member is linked with the torque transmission shaft through a first helical spline coupling including the first outer helical spline. Axial movement of the outer member with respect to the torque transmission shaft is regulated. The outer member is linked with the intermediate member through a second helical spline coupling. The first spring biases the intermediate member in the first axial direction. The second spring biases the intermediate member in the second axial direction.

APPLICATIONS**

This application claims the benefit of priority to Japanese Patent Application No. 2021-194872 filed on Nov. 30, 2021. The entire contents of this application are hereby incorporated herein by reference.

BACKGROUND OF THE INVENTION

1. Field of the Invention

The present invention relates to a vessel propulsion apparatus, a vessel, an auxiliary machine-equipped engine, and a torque fluctuation absorber.

2. Description of the Related Art

Conventionally, in small vessels, automobiles, and others, air is compressed by using a supercharger and supplied to an engine. US 2007/0079796 A1 has disclosed an installation structure of a supercharger. According to this structure, a driving gear of the supercharger is provided with a one-way clutch as a torque fluctuation absorber. When an engine is decreased in rotational frequency upon deceleration or the like to result in a sudden torque fluctuation, the one-way clutch is actuated to absorb the torque fluctuation.

SUMMARY OF THE INVENTION

The inventor of preferred embodiments of the present invention described and claimed in the present application conducted an extensive study and research regarding a vessel propulsion apparatus, a vessel, an auxiliary machine-equipped engine, and a torque fluctuation absorber such as the one described above, and in doing so, discovered and first recognized new unique challenges and previously unrecognized possibilities for improvements as described in greater detail below.

Absorption of a torque fluctuation caused when an engine is increased in rotational frequency upon acceleration or the like of the engine is also preferable.

Preferred embodiments of the present invention provide vessel propulsion apparatuses, vessels, auxiliary machine-equipped engines, and torque fluctuation absorbers which are each capable of absorbing a bidirectional torque fluctuation.

In order to overcome the previously unrecognized and unsolved challenges described above, a preferred embodiment of the present invention provides a vessel propulsion apparatus including an engine that includes a crank shaft, a supercharger that includes an input shaft, a gear train that includes a plurality of gears to transmit a driving force from the crank shaft to the supercharger, and a torque fluctuation absorber to absorb a fluctuation in torque transmitted to the gear train. The torque fluctuation absorber includes a first outer helical spline, an intermediate member, an outer member, a first spring, and a second spring. The first outer helical spline is rotatable integrally with a torque transmission shaft which includes at least one of the crank shaft, the input shaft, and an intermediate shaft located in a torque transmission path from the crank shaft to the input shaft. The intermediate

member coaxially surrounds the torque transmission shaft, and is able to move in a first axial direction and in a second axial direction which is an opposite direction to the first axial direction. The intermediate member includes a first inner helical spline on an inner circumference thereof and a second outer helical spline on an outer circumference thereof. The first inner helical spline is engaged with the first outer helical spline to provide a first helical spline coupling. The outer member coaxially surrounds the torque transmission shaft, and is regulated in axial movement with respect to the torque transmission shaft. The outer member includes teeth on an outer circumference thereof and a second inner helical spline on an inner circumference thereof. The teeth mesh with corresponding gears of the gear train. The second inner helical spline is engaged with the second outer helical spline to provide a second helical spline coupling. The first spring biases the intermediate member in the first axial direction. The second spring biases the intermediate member in the second axial direction.

According to this structural arrangement, the torque fluctuation absorber includes the intermediate member, the outer member, the first spring to bias the intermediate member in the first axial direction, and the second spring to bias the intermediate member in the second axial direction. The teeth which mesh with corresponding gears of the gear train are provided on the outer circumference of the outer member. The intermediate member coaxially surrounds the torque transmission shaft. The intermediate member is able to move in the first axial direction and in the second axial direction.

The intermediate member is linked with the torque transmission shaft through the first helical spline coupling and linked with the outer member through the second helical spline coupling. When a torque fluctuation occurs in the torque transmission path, due to actions of the first and the second helical spline coupling, the intermediate member is moved in the second axial direction in resistance to the first spring. It is also moved in the first axial direction in resistance to the second spring. Therefore, it is possible to absorb a bidirectional torque fluctuation.

In a preferred embodiment of the present invention, the vessel propulsion apparatus further includes an inner member which coaxially surrounds the torque transmission shaft, is regulated in axial movement with respect to the torque transmission shaft, and is rotatable integrally with the torque transmission shaft. The first outer helical spline is provided on an outer circumference of the inner member. According to this structural arrangement, the inner member which surrounds the torque transmission shaft coaxially is regulated in axial movement with respect to the torque transmission shaft and is rotatable integrally with the torque transmission shaft. The first outer helical spline to provide the first helical spline coupling is provided on the outer circumference of the inner member. The torque fluctuation absorber may have a higher versatility by using the inner member.

In a preferred embodiment of the present invention, the torque fluctuation absorber further includes a base which coaxially surrounds the torque transmission shaft and is fixed to the torque transmission shaft. On an outer circumference of the base, the inner member is rotatable integrally therewith while being regulated in axial movement. The torque fluctuation absorber further includes a first support and a second support, each of which includes an annular linkage that is linked with the base and regulated in axial movement with respect to the base and an annular extension which extends outward in a radial direction from the annular linkage. The first support and the second support regulate an

axial movement of the outer member between their respective extensions. The first spring is interposed between the annular extension of the first support and the intermediate member. The second spring is interposed between the annular extension of the second support and the intermediate member.

According to this structural arrangement, the inner member is able to rotate integrally with respect to the base fixed to the torque transmission shaft and also regulated in axial movement. The annular linkage of the first support and the annular linkage of the second support are linked with the base and also regulated in axial movement with respect to the base. Therefore, the first support and the second support are regulated in axial movement with respect to the base. The outer member is regulated in axial movement between the annular extension of the first support and the annular extension of the second support. When a torque fluctuation occurs in the torque transmission path, due to actions of the first or the second helical spline coupling, the intermediate member interposed between the outer member and the inner member is moved in the first axial direction or in the second axial direction. When the intermediate member is moved in the second axial direction, the first spring is compressed between the annular extension of the first support and the intermediate member. When the intermediate member is moved in the first axial direction, the second spring is compressed between the annular extension of the second support and the intermediate member. Therefore, it is possible to absorb a bidirectional torque fluctuation.

In a preferred embodiment of the present invention, at least one of the annular extension of the first support and the annular extension of the second support supports the outer member so as to rotate coaxially with the torque transmission shaft. According to this structural arrangement, it is possible to support the outer member so as to be rotatable coaxially with the torque transmission shaft by at least one of the annular extension of the first support and the annular extension of the second support.

In a preferred embodiment of the present invention, one of the annular extension of the first support and the annular extension of the second support supports the outer circumference of the outer member so as to be rotatable coaxially with the torque transmission shaft. The other of the annular extension of the first support and the annular extension of the second support supports the inner circumference of the outer member so as to be rotatable coaxially with the torque transmission shaft. According to this structural arrangement, it is possible to support each of the outer circumference and the inner circumference of the outer member so as to rotate by the annular extension of a corresponding support.

In a preferred embodiment of the present invention, at least one of the annular extension of the first support and the annular extension of the second support supports the intermediate member so as to be rotatable coaxially with the torque transmission shaft. According to this structural arrangement, it is possible to support the intermediate member so as to rotate coaxially with the torque transmission shaft by at least one of the annular extension of the first support and the annular extension of the second support.

In a preferred embodiment of the present invention, either one of the first support and the second support is unitary and integral with the base. The other of the first support and the second support is fitted onto the outer circumference of the base and supported while being regulated in axial movement with respect to the base. According to this structural arrangement, either one of the first support and the second support

is integral with the base as a single member. Therefore, it is possible to make the structure simple.

In a preferred embodiment of the present invention, the torque fluctuation absorber further includes a housing which 5 houses the inner member, the intermediate member, the first spring, and the second spring. The housing is defined by the base, the outer member, the first support, and the second support. According to this structural arrangement, it is possible to house the inner member, the intermediate member, 10 the first spring, and the second spring in the housing defined by the base, the outer member, the first support, and the second support.

In a preferred embodiment of the present invention, the torque fluctuation absorber further includes a sub-assembly 15 which includes the base, the inner member, the intermediate member, the outer member, the first spring, and the second spring. According to this structural arrangement, it is possible to assemble the sub-assembly in advance and incorporate the sub-assembly in the torque transmission shaft. It 20 is, therefore, possible to improve ease of assembly.

In a preferred embodiment of the present invention, the first spring and the second spring have a different spring constant from each other. According to this structural arrangement, depending on a direction in which the intermediate member moves upon occurrence of a torque fluctuation, a spring load to resist the movement of the intermediate member is able to be different.

In a preferred embodiment of the present invention, the first spring has a larger spring constant than the second spring. According to this structural arrangement, the spring load of the first spring to resist a movement of the intermediate member in the second axial direction is able to be larger than the spring load of the second spring to resist a movement of the intermediate member in the first axial direction.

In a preferred embodiment of the present invention, the first spring includes a disc spring, and the second spring includes a helical compression spring. According to this structural arrangement, the disc spring as the first spring may 40 be increased in spring constant progressively in relation to a flexing displacement. Therefore, a high spring load may be obtained in resistance to the movement of the intermediate member in the second axial direction. It is possible to enhance the effect of absorbing a torque fluctuation.

In a preferred embodiment of the present invention, at 45 least one of the first inner helical spline and the second outer helical spline is inclined with respect to a central axis of the intermediate member so that the intermediate member is moved in the second axial direction, which is a direction in which the first spring is compressed when a positive torque is transmitted from the crank shaft to the supercharger. According to this structural arrangement, when a positive torque is transmitted from the crank shaft to the supercharger, the intermediate member is moved in the second 50 axial direction, which is a direction in which the first spring higher in spring constant is compressed. Therefore, a torque fluctuation is effectively absorbed.

Another preferred embodiment of the present invention provides a vessel which includes the vessel propulsion apparatus. According to this structural arrangement, it is possible to provide the same effects as those of the vessel propulsion apparatus in each of the preferred embodiments described above.

Another preferred embodiment of the present invention provides an auxiliary machine-equipped engine which 60 includes an engine that includes a crank shaft, an auxiliary machine that includes an input shaft, a gear train that

includes a plurality of gears to transmit a driving force from the crank shaft to the auxiliary machine, and a torque fluctuation absorber to absorb a fluctuation in torque transmitted to the gear train. The torque fluctuation absorber includes a first outer helical spline, an intermediate member, an outer member, a first spring, and a second spring. The first outer helical spline is rotatable integrally with a torque transmission shaft that includes at least one of the crank shaft, the input shaft, and an intermediate shaft located in a torque transmission path from the crank shaft to the input shaft. The intermediate member coaxially surrounds the torque transmission shaft, and is able to move in a first axial direction and in a second axial direction which is an opposite direction to the first axial direction. The intermediate member includes a first inner helical spline on an inner circumference thereof. The first inner helical spline is engaged with the first outer helical spline to provide a first helical spline coupling. The intermediate member includes a second outer helical spline on an outer circumference thereof. The outer member coaxially surrounds the torque transmission shaft, and is regulated in axial movement with respect to the torque transmission shaft. The outer member includes teeth on an outer circumference thereof. The teeth mesh with corresponding gears of the gear train. The outer member includes a second inner helical spline on an inner circumference thereof. The second inner helical spline is engaged with the second outer helical spline to provide a second helical spline coupling. The first spring biases the intermediate member in the first axial direction. The second spring biases the intermediate member in the second axial direction.

According to this structural arrangement, the intermediate member is linked with the torque transmission shaft through the first helical spline coupling and linked with the outer member through the second helical spline coupling. When a torque fluctuation occurs in the torque transmission path, due to actions of the first or the second helical spline coupling, the intermediate member is moved in the second axial direction in resistance to the first spring or moved in the first axial direction in resistance to the second spring. Therefore, it is possible to absorb a bidirectional torque fluctuation in the auxiliary machine-equipped engine.

Another preferred embodiment of the present invention provides a torque fluctuation absorber to absorb a fluctuation in torque transmitted to a gear train including a plurality of gears. The torque fluctuation absorber includes a first outer helical spline, an intermediate member, an outer member, a first spring, and a second spring. The first outer helical spline is rotatable integrally with a torque transmission shaft. The intermediate member coaxially surrounds the torque transmission shaft, and is able to move in a first axial direction and in a second axial direction which is an opposite direction to the first axial direction. The intermediate member includes a first inner helical spline on an inner circumference thereof. The first inner helical spline is engaged with the first outer helical spline to provide a first helical spline coupling. The intermediate member includes a second outer helical spline on an outer circumference thereof. The outer member coaxially surrounds the torque transmission shaft, and is regulated in axial movement with respect to the torque transmission shaft. The outer member includes teeth on an outer circumference thereof. The teeth mesh with corresponding gears of the gear train. The outer member includes a second inner helical spline on an inner circumference thereof. The second inner helical spline is engaged with the second outer helical spline to provide a second helical spline coupling. The first spring biases the intermediate member in

the first axial direction. The second spring biases the intermediate member in the second axial direction.

According to this structural arrangement, the intermediate member is linked with the torque transmission shaft through the first helical spline coupling and linked with the outer member through the second helical spline coupling. When a torque fluctuation occurs in a torque transmission path, due to actions of the first or the second helical spline coupling, the intermediate member is moved in the second axial direction in resistance to the first spring or moved in the first axial direction in resistance to the second spring. Therefore, it is possible to absorb a bidirectional fluctuation in torque transmitted to the gear train.

The above and other elements, features, steps, characteristics and advantages of the present invention will become more apparent from the following detailed description of the preferred embodiments with reference to the attached drawings.

BRIEF DESCRIPTION OF THE DRAWINGS

FIG. 1 is a schematic view which shows a left side surface of a jet propulsion watercraft that includes a vessel propulsion apparatus according to a preferred embodiment of the present invention.

FIG. 2 is a cross-sectional view which shows a supercharger, a gear train, and a torque fluctuation absorber installed on an engine.

FIG. 3 is a schematic front view of the gear train.

FIG. 4 is a schematic exploded perspective view of the torque fluctuation absorber.

FIG. 5 is a schematic exploded perspective view of the torque fluctuation absorber when viewed at a different angle.

FIG. 6A and FIG. 6B are each a schematic perspective view of the torque fluctuation absorber when viewed at angles different from each other.

FIG. 7 is an enlarged cross-sectional view which shows major components of the torque fluctuation absorber.

FIG. 8A and FIG. 8B are each an explanatory view for describing functions of a first helical spline coupling.

FIG. 9A and FIG. 9B are each an explanatory view for describing functions of a second helical spline coupling.

FIG. 10 is a cross-sectional view which shows one operational condition of the torque fluctuation absorber.

FIG. 11 is a cross-sectional view which shows another operational condition of the torque fluctuation absorber.

FIG. 12 is a cross-sectional view which shows a preferred modified example of the torque fluctuation absorber.

FIG. 13 is a cross-sectional view which shows another preferred modified example of the torque fluctuation absorber.

FIG. 14 is an enlarged cross-sectional view which shows major components of a torque fluctuation absorber in an auxiliary machine-equipped engine according to a preferred embodiment of the present invention.

DETAILED DESCRIPTION OF THE PREFERRED EMBODIMENTS

FIG. 1 is a schematic view which shows a left side surface of a vessel including a vessel propulsion apparatus according to a preferred embodiment of the present invention. As shown in FIG. 1, a vessel 100 includes a vessel body 101, and a vessel propulsion apparatus P1 which propels the vessel body 101. The vessel propulsion apparatus P1 includes a jet pump 102 which propels the vessel body 101 and an engine 120 which drives the jet pump 102. The jet

pump 102 suctions water from a vessel bottom by a driving force of the engine 120 and jets out the water to the outside of the vessel body 101. The vessel of the present preferred embodiment is a jet propulsion watercraft. The vessel 100 further includes a handle 103 operated from side to side by a crew member and a seat 104 occupied by the crew member.

The vessel body 101 includes a hull 105 which floats on the surface of water and a deck 106 which is located higher than the water surface. The deck 106 is located above the hull 105 which provides the vessel bottom. The engine 120 is located between the hull 105 and the deck 106 in an up/down direction. The engine 120 is located inside an engine room provided in an interior of the vessel body 101. The jet pump 102 is located behind the engine 120.

The jet pump 102 includes an intake 107 which is open at the vessel bottom, an outlet 108 which jets rearward water suctioned through the intake 107, and a flow channel 109 which guides the water suctioned through the intake 107 to the outlet 108. The jet pump 102 further includes an impeller 110 (rotor vane) and a stator vane 111 which are disposed in the flow channel 109 as well as a drive shaft 112 which rotates together with the impeller 110. The jet pump 102 also includes a nozzle 113 which defines the outlet 108 and a deflector 114 which deflects the direction of water flow that flows rearward from the nozzle 113 to the right side or the left side. The deflector 114 defines a jet port 115 which opens rearward.

An output of the engine 120 is adjusted by a crew member that operates a throttle lever provided in the handle 103. When the engine 120 rotates the drive shaft 112, the impeller 110 is rotated around a center line of the drive shaft 112 generating a suction force that suctions water outside the vessel from the intake 107 to the flow channel 109. The water suctioned into the flow channel 109 passes through the impeller 110, the stator vane 111, the nozzle 113, and the deflector 114 in this order and is jetted rearward from the jet port 115 of the deflector 114. Thus, a thrust to propel the vessel 100 forward is generated. Further, the deflector 114 is pivoted from side to side depending on operation of the handle 103 and, therefore, a direction in which water is jetted from the jet pump 102 is changed to the right side or to the left side depending on the operation of the handle 103. Thus, the vessel 100 is steered.

The engine 120 is an internal combustion engine. The engine 120 includes a crank shaft 1 capable of rotating around a crank axis Ac that extends in a front and rear direction. The engine 120 includes a plurality of cylinders 122 which respectively house a plurality of pistons 121 that reciprocate in an up/down direction and a connecting rod 123 that links each of the plurality of pistons 121 with the crank shaft 1.

The engine 120 further includes a supercharger 130, a gear train GT which transmits a driving force from the crank shaft 1 to the supercharger 130, and a torque fluctuation absorber TFA which absorbs a fluctuation in torque transmitted to the gear train GT.

FIG. 2 is a cross-sectional view of the supercharger 130, the gear train GT, and the torque fluctuation absorber TFA which are installed on the engine 120. The crank shaft 1 protrudes from a front end 120b of a body 120a of the engine 120. Hereinafter, the direction of extension from a protruding portion of the crank shaft 1 to an interior of the engine 120 is referred to as a first axial direction X1, and an opposite direction to the first axial direction X1 is referred to as a second axial direction X2. The supercharger 130 compresses air due to the power from the crank shaft 1. The

supercharger 130 is a mechanical supercharger (S/C). The supercharger 130 is arranged to compress air due to the power transmitted from the crank shaft 1. The supercharger 130 includes a ventilation channel 131 and an intercooler 132.

The ventilation channel 131 connects the supercharger 130 with each of the cylinders 122 of the engine 120. Compressed air which has been compressed by the supercharger 130 passes through the ventilation channel 131 and flows into each of the cylinders 122. The intercooler 132 is located in the ventilation channel 131. The intercooler 132 is located to cool high-temperature compressed air flowing through the ventilation channel 131.

The gear train GT includes a plurality of gears to transmit a driving force of the crank shaft 1 to the supercharger 130. A preferred example of the gear train GT includes a driving gear G1, a first intermediate gear G2, a second intermediate gear G3, and a driven gear G4.

The supercharger 130 includes a housing 133 which includes an air intake port 134 and an ejection port 135. The housing 133 is installed on an installation portion 124 provided at the front end 120b of the body 120a of the engine 120. The air intake port 134 takes in air fed from an air intake box BX. The ejection port 135 sends the air taken in from the air intake port 134 to the intercooler 132. A rotary portion 136 is installed in an interior of the housing 133. The rotary portion 136 includes an input shaft 137 and an impeller 138. The input shaft 137 is supported by the housing 133 so as to rotate through a bearing 139. The impeller 138 is linked with one end portion of the input shaft 137 and rotates integrally with the input shaft 137. The impeller 138 is disposed inside the air intake port 134.

As the driven gear G4, an input gear is installed on the other end portion of the input shaft 137. The driven gear G4 is linked with the driving gear G1 through the first intermediate gear G2 and the second intermediate gear G3. The first intermediate gear G2 and the second intermediate gear G3 are located coaxially on an intermediate shaft 140 functioning as a torque transmission shaft which is located in a torque transmission path from the crank shaft 1 to the input shaft 137 of the supercharger 130. The intermediate shaft 140 is a hollow shaft. A supporting shaft 150 which is fixed to the housing 133 is inserted into the intermediate shaft 140. A central axis of the supporting shaft 150 and a central axis of the intermediate shaft 140 are parallel or substantially parallel to the crank axis Ac. The intermediate shaft 140 is supported by the supporting shaft 150 so as to rotate through a bearing (not shown).

The first intermediate gear G2 and the second intermediate gear G3 are located on an outer circumference of the intermediate shaft 140 and separated in an axial direction of the intermediate shaft 140. The first intermediate gear G2 and the second intermediate gear G3 rotate integrally with the intermediate shaft 140. The first intermediate gear G2 is engaged with the driving gear G1. The second intermediate gear G3 is engaged with the driven gear G4. When the crank shaft 1 is rotated by actuation of the engine 120, a rotary force thereof is transmitted to the input shaft 137 through the gear train GT which includes the driving gear G1, the first intermediate gear G2, the second intermediate gear G3, and the driven gear G4. Thus, the impeller 138 is rotated. Air which is introduced into the air intake port 134 is compressed by the rotation of the impeller 138 and ejected from the ejection port 135. The compressed air ejected from the ejection port 135 is cooled by the intercooler 132 and, thereafter, supplied to each of the cylinders 122 of the engine 120.

FIG. 3 is a schematic front view of the gear train GT. As shown in FIG. 3, the first intermediate gear G2 is a gear having an outer diameter smaller than that of the driving gear G1. Therefore, the intermediate shaft 140 is rotated at a rotational speed higher than that of the crank shaft 1. The second intermediate gear G3 is a gear having an outer diameter larger than that of the first intermediate gear G2. The second intermediate gear G3 is a gear having an outer diameter larger than that of the driven gear G4. Therefore, the input shaft 137 of the supercharger 130 is rotated at a rotational speed higher than that of the intermediate shaft 140. Each of the crank shaft 1, the intermediate shaft 140, and the input shaft 137 of the supercharger 130 is a component of the torque transmission shaft TT. The torque fluctuation absorber TFA is disposed at least on one torque transmission shaft TT. In the present preferred embodiment, the torque fluctuation absorber TFA is located around the crank shaft 1.

FIG. 4 and FIG. 5 are each an exploded perspective view of a preferred example of the torque fluctuation absorber TFA provided in the driving gear G1 when viewed at angles different from each other. As shown in FIG. 4, the torque fluctuation absorber TFA includes a base 2, an inner member 3, an intermediate member 4, an outer member 5, a first spring 6, a second spring 7, a first supporting member 8, a second supporting member 9, a spring guide 10, and a retaining ring 11. In the present preferred embodiment, the base 2 and the first supporting member 8 are integral and defined as a single member. The torque fluctuation absorber TFA further includes a first outer helical spline 31, a first inner helical spline 41, a second outer helical spline 42, and a second inner helical spline 52.

The first outer helical spline 31 is provided on an outer circumference 3a of the inner member 3. The first inner helical spline 41 is provided on an inner circumference 4b of the intermediate member 4. The first outer helical spline 31 and the first inner helical spline 41 are engaged with each other to provide a first helical spline coupling HC1. The second outer helical spline 42 is provided on an outer circumference 4a of the intermediate member 4. The second inner helical spline 52 is provided on an inner circumference 5b of the outer member 5. The second outer helical spline 42 and the second inner helical spline 52 are engaged with each other to provide a second helical spline coupling HC2.

As shown in FIG. 5, one example of the first spring 6 is a disc spring. The disc spring may be used solely or a plurality of them may be used by being stacked. An annular housing recessed portion 4e to house the first spring 6 is provided in the intermediate member 4. A preferred example of the second spring 7 includes a helical compression spring. Where the second spring 7 includes a helical compression spring, a plurality of the second springs 7 are provided and located at equal or substantially equal intervals in the circumferential direction around the crank axis Ac. A housing recessed portion 9g to house a corresponding second spring 7 is provided in the second supporting member 9. The spring guide 10 includes a tubular portion 10a which houses and surrounds one end of the second spring 7 and a bottom portion 10b which closes one end of the tubular portion 10a and receives one end of the second spring 7. The first spring 6 and the second spring 7 have a different spring constant from each other. The spring constant of the first spring 6 is larger than that of the second spring 7.

FIG. 6A and FIG. 6B are each a schematic perspective view of the torque fluctuation absorber TFA, when viewed at angles different from each other. As shown in FIG. 6A, a plurality of elements which define the torque fluctuation

absorber TFA are assembled together at a stage before being installed on the crank shaft 1, thus defining a sub-assembly SA. Further, as shown in FIG. 6B, the second supporting member 9 is held by being fitted onto an outer circumference 5 of the base 2. The retaining ring 11 is installed on the base 2 and arranged so that the second supporting member 9 will not come off the base 2 in the first axial direction X1. The retaining ring 11 is a preferred example of a regulating member to regulate an axial movement of the second supporting member 9.

FIG. 7 is an enlarged cross-sectional view which shows major components of the torque fluctuation absorber TFA provided in the driving gear G1. As shown in FIG. 7, the base 2 is ring-shaped and coaxially surrounds the crank shaft 1 (torque transmission shaft TT). The base 2 is fixed to the crank shaft 1. The base 2 is regulated in axial movement with respect to the crank shaft 1. The base 2 includes an outer circumference 2a, an inner circumference 2b, one end 2c and the other end 2d in an axial direction, an inner peripheral spline 2e, an inner circumference flange 2f, a first outer peripheral spline 2g, a second outer peripheral spline 2h, and an outer circumference groove 2j. The inner peripheral spline 2e, the first outer peripheral spline 2g, and the second outer peripheral spline 2h are all straight splines.

The inner peripheral spline 2e is provided on the inner circumference 2b. The base 2 is fitted onto an outer circumference 1a of the crank shaft 1. The base 2 is spline-coupled to the crank shaft 1. The inner peripheral spline 2e is engaged with an outer peripheral spline 1b on the outer circumference 1a of the crank shaft 1. Thus, the base 2 is coupled to the crank shaft 1 so as to rotate integrally therewith. The inner circumference flange 2f is an annular flange which extends inward in a radial direction from the inner circumference 2b. The inner circumference flange 2f abuts against an end surface 1c of the crank shaft 1. The inner circumference flange 2f is fastened to the end surface 1c of the crank shaft 1 by a fixing screw 12, which is an example of a fastening member that penetrates through the inner circumference flange 2f. Thus, the base 2 is fixed to the crank shaft 1.

The base 2 is integral with the first supporting member 8 as a single member. The first supporting member 8 is an annular member which extends outward in a radial direction from the one end 2c of the base 2. The first outer peripheral spline 2g, the second outer peripheral spline 2h, and the outer circumference groove 2j are provided on the outer circumference 2a. The first outer peripheral spline 2g is located adjacent to the one end 2c. The second outer peripheral spline 2h extends from the other end 2d up to a position adjacent to the first outer peripheral spline 2g.

The second supporting member 9 is an annular member. The second supporting member 9 is fitted onto the outer circumference 2a of the base 2. The second supporting member 9 is spline-coupled to the second outer peripheral spline 2h on the outer circumference 2a of the base 2. Thus, the second supporting member 9 is coupled to the base 2 so as to rotate integrally therewith. An axial movement of the second supporting member 9 with respect to the base 2 is regulated by a regulating member. An axial movement of the second supporting member 9 with respect to the base 2 is regulated by the retaining ring 11, which is an example of the regulating member that is fitted onto the outer circumference groove 2j. Thus, the second supporting member 9 is regulated in axial movement with respect to the crank shaft 1.

The inner member 3 is a ring-shaped member which coaxially surrounds the crank shaft 1. The inner member 3 rotates integrally with the crank shaft 1. The inner member

11

3 coaxially surrounds the base 2. The inner member 3 includes the outer circumference 3a, an inner circumference 3b, one end 3c, and the other end 3d in an axial direction, an inner peripheral spline 3e, and a first outer helical spline 31. The inner peripheral spline 3e is a straight spline which is provided on the inner circumference 3b. The inner member 3 is spline-coupled to the outer circumference 3a of the base 2. The inner peripheral spline 3e of the inner member 3 is engaged with the first outer peripheral spline 2g of the base 2. Thus, the inner member 3 rotates integrally with the base 2.

The inner member 3 is held in an axial direction between the first supporting member 8 and the second supporting member 9. The one end 3c of the inner member 3 abuts against the first supporting member 8. The other end 3d of the inner member 3 abuts against the second supporting member 9. Thus, the inner member 3 is regulated in axial movement with respect to the base 2. The inner member 3 is held on the outer circumference 2a of the base 2 so as to rotate integrally therewith in a state of being regulated in axial movement. The inner member 3 is regulated in axial movement with respect to the crank shaft 1. The first outer helical spline 31 is provided on the outer circumference 3a of the inner member 3.

The intermediate member 4 is a ring-shaped member which coaxially surrounds the crank shaft 1. The intermediate member 4 coaxially surrounds the inner member 3. The intermediate member 4 is helical spline-coupled to the inner member 3. The intermediate member 4 includes the outer circumference 4a, the inner circumference 4b, an end surface 4c and an end surface 4d in an axial direction, the first inner helical spline 41, the second outer helical spline 42, the housing recessed portion 4e, and an annular raised portion 4f.

The first inner helical spline 41 is provided on the inner circumference 4b of the intermediate member 4. The first inner helical spline 41 of the intermediate member 4 is engaged with the first outer helical spline 31 of the inner member 3. The first outer helical spline 31 and the first inner helical spline 41 are engaged with each other to provide the first helical spline coupling HC1. The second outer helical spline 42 is provided on the outer circumference 4a of the intermediate member 4.

One end surface 4c faces the first supporting member 8. The housing recessed portion 4e is an annular recessed portion which is provided on the one end surface 4c and is coaxial with the ring-shaped intermediate member 4. The first spring 6 is housed in the housing recessed portion 4e. The annular raised portion 4f protrudes from the other end surface 4d in the first axial direction X1. The annular raised portion 4f is coaxial with the ring-shaped intermediate member 4. The annular raised portion 4f is coaxial with the crank shaft 1. The annular raised portion 4f includes an outer peripheral surface 4g and an inner peripheral surface 4h which are coaxial with the crank shaft 1.

The outer member 5 is a ring-shaped member which coaxially surrounds the crank shaft 1. The outer member 5 is regulated in axial movement with respect to the crank shaft 1. The outer member 5 coaxially surrounds the intermediate member 4. The outer member 5 is helical spline-coupled to the intermediate member 4. The outer member 5 includes an outer circumference 5a, the inner circumference 5b, an end surface 5c and an end surface 5d in an axial direction, an inner peripheral recessed portion 5e, an annular step portion 5f, an outer peripheral recessed portion 5g, a plurality of teeth 5h, and a second inner helical spline 52.

12

The plurality of teeth 5h are provided on the outer circumference 5a of the outer member 5.

The plurality of teeth 5h mesh with the first intermediate gear G2. The second inner helical spline 52 is provided on the inner circumference 5b of the outer member 5. The second inner helical spline 52 of the outer member 5 is engaged with the second outer helical spline 42 of the intermediate member 4. The second helical spline coupling HC2 is provided by the second inner helical spline 52 of the outer member 5 and the second outer helical spline 42 of the intermediate member 4.

One end surface 5c is adjacent to the first supporting member 8. The other end surface 5d faces the second supporting member 9. The inner peripheral recessed portion 5e is provided on the inner circumference 5b and opens to the one end surface 5c. The inner peripheral recessed portion 5e is coaxial with respect to the ring-shaped outer member 5. The inner peripheral recessed portion 5e is a cylindrical surface which is coaxial with the crank shaft 1. The inner peripheral recessed portion 5e is an example of a supported portion which is supported by the first supporting member 8. The annular step portion 5f is a step portion perpendicular or substantially perpendicular to the inner peripheral recessed portion 5e and parallel or substantially parallel to the one end surface 5c. The annular step portion 5f is an example of a held-between portion. The annular step portion 5f is a surface which is perpendicular or substantially perpendicular to the crank axis Ac.

The outer peripheral recessed portion 5g is provided on the outer circumference 5a and opens to the other end surface 5d. The other end surface 5d is a preferred example of the held-between portion. The outer peripheral recessed portion 5g is coaxial with respect to the ring-shaped outer member 5. The outer peripheral recessed portion 5g is a cylindrical surface which is coaxial with the crank axis Ac. The outer peripheral recessed portion 5g is an example of a supported portion which is supported by the second supporting member 9.

The first supporting member 8 is a ring-shaped member which is coaxial with the crank shaft 1. The first supporting member 8 includes an annular linkage portion 8a, an annular extension portion 8b, an end surface 8c and an end surface 8d in an axial direction, an outer peripheral surface 8e, an annular raised portion 8f, and an annular raised portion 8g. The annular linkage portion 8a of the first supporting member 8 is linked integrally with the one end 2c of the base 2. The annular extension portion 8b extends outward in a radial direction from the annular linkage portion 8a. One end surface 8c defines a portion of an outer surface of the driving gear G1. The outer peripheral surface 8e of the first supporting member 8 is equivalent to an outer peripheral surface of the extension portion 8b. The outer peripheral surface 8e is a cylindrical surface which is coaxial with the crank shaft 1. The outer peripheral surface 8e is fitted into the inner peripheral recessed portion 5e of the outer member 5. Thus, the extension portion 8b of the first supporting member 8 has a function of supporting the outer member 5 so as to rotate coaxially with the crank shaft 1.

The annular raised portion 8f is provided on the other end surface 8d so as to be adjacent to the outer peripheral surface 8e. The annular raised portion 8f is in contact with the annular step portion 5f of the outer member 5 so as to slide thereon. The annular raised portion 8f has a function of regulating an axial movement of the outer member 5. Thus, the extension portion 8b of the first supporting member 8 has the function of regulating an axial movement of the outer member 5.

The annular raised portion **8g** is located farther inward in a radial direction than the annular raised portion **8f** in the extension portion **8b**. The annular raised portion **8g** protrudes from the other end surface **8d**. The annular raised portion **8g** is coaxial with the ring-shaped first supporting member **8**. The annular raised portion **8g** is coaxial with the crank shaft **1**. The annular raised portion **8g** includes an outer circumference **8h**, an inner circumference **8j**, and a top portion **8k** that is an example of a receiving portion. The outer circumference **8h** and the inner circumference **8j** of the annular raised portion **8g** define a cylindrical surface which is coaxial with the crank shaft **1**. The annular raised portion **8g** is fitted into the housing recessed portion **4e** of the one end surface **5c** of the intermediate member **4**. Thus, the first supporting member **8** has a function of supporting the intermediate member **4** so as to rotate coaxially with the crank shaft **1**. The extension portion **8b** of the first supporting member **8** also has a function of supporting the intermediate member **4** so as to move in an axial direction.

The first spring **6** is interposed between the extension portion **8b** of the first supporting member **8** and the intermediate member **4**. The first spring **6** is flexed between the extension portion **8b** of the first supporting member **8** and the intermediate member **4**. The first spring **6** biases the intermediate member **4** in the first axial direction **X1**. The first spring **6** is interposed between the top portion **8k** of the annular raised portion **8g** provided in the extension portion **8b** of the first supporting member **8** and the bottom of the housing recessed portion **4e** of the intermediate member **4**. The first spring **6** biases the intermediate member **4** in the first axial direction **X1**.

The second supporting member **9** is a ring-shaped member which is coaxial with the crank shaft **1**. The second supporting member **9** includes an annular linkage portion **9a**, an annular extension portion **9b**, an end surface **9c** and an end surface **9d** in an axial direction, an outer circumference **9e**, an annular raised portion **9f**, the housing recessed portion **9g**, and an annular recessed portion **9h**. The annular linkage portion **9a** of the second supporting member **9** is linked integrally with the other end **2d** of the base **2**. The annular linkage portion **9a** of the second supporting member **9** is spline-coupled to the outer circumference **2a** of the base **2**. An inner peripheral spline **9j** which is a straight spline provided in the linkage portion **9a** is engaged with the second outer peripheral spline **2h** on the outer circumference **2a** of the base **2**. The second supporting member **9** rotates integrally with the base **2**. The annular extension portion **8b** extends outward in a radial direction from the annular linkage portion **8a**. The outer circumference **9e** of the second supporting member **9** is equivalent to an outer circumference of the extension portion **9b**. One end surface **9c** is also an outer surface of the driving gear **G1**.

The annular raised portion **9f** protrudes from the other end surface **9d** in the extension portion **9b**. The annular raised portion **9f** is located adjacent to the outer circumference **9e**. An inner peripheral surface **9k** of the annular raised portion **9f** is a cylindrical surface coaxial with the crank shaft **1**. The inner peripheral surface **9k** of the annular raised portion **9f** is fitted into the outer peripheral recessed portion **5g** of the outer member **5** so as to slide thereon. Thus, the extension portion **9b** of the second supporting member **9** provides the function of supporting the outer member **5** so as to rotate coaxially with the crank shaft **1**. The annular raised portion **9f** is in contact with the other end surface **5d** of the outer member **5** so as to slide thereon. Thus, the extension portion **9b** of the second supporting member **9** provides the function of regulating an axial movement of the outer member **5**.

The housing recessed portion **9g** and the annular recessed portion **9h** are provided on the other end surface **9d** in the extension portion **9b**. The housing recessed portion **9g** is located farther outward in a radial direction than the annular recessed portion **9h**. The housing recessed portion **9g** is coaxial with the ring-shaped second supporting member **9**. The housing recessed portion **9g** is coaxial with the crank shaft **1**. The annular raised portion **4f** of the intermediate member **4** is fitted into the housing recessed portion **9g** so as to slide thereon. Thus, the extension portion **9b** of the second supporting member **9** has the function of supporting the intermediate member **4** so as to rotate coaxially with the crank shaft **1**. The extension portion **9b** of the second supporting member **9** also has the function of supporting the intermediate member **4** so as to move in an axial direction.

The housing recessed portion **9g** houses the second spring **7**. The second spring **7** is interposed between the extension portion **9b** of the second supporting member **9** and the intermediate member **4**. The second spring **7** is flexed between the extension portion **9b** of the second supporting member **9** and the intermediate member **4**. The second spring **7** biases the intermediate member **4** in the second axial direction **X2**. A preferred example of the second spring **7** is a helical compression spring. The second spring **7** is interposed between the bottom of the annular recessed portion **9h** provided in the extension portion **9b** of the second supporting member **9** and the other end surface **4d** of the intermediate member **4**. The bottom portion **10b** of the spring guide **10** is interposed between the other end surface **4d** of the intermediate member **4** and the second spring **7**. The bottom portion **10b** is slidable with respect to the other end surface **4d**.

Due to being surrounded by the base **2**, the outer member **5**, the first supporting member **8**, and the second supporting member **9**, a housing space **SS** is provided in which the inner member **3**, the intermediate member **4**, the first spring **6**, and the second spring **7** are housed.

FIG. 8A and FIG. 8B are each an explanatory view for describing functions of the first helical spline coupling **HC1**. FIG. 8A shows a case in which a positive torque **PT** is transmitted from the crank shaft **1** to the supercharger **130** through the gear train **GT**. In this case, an axial component **M2** of an engaging force **M** imparted from a tooth surface **31a** of the first outer helical spline **31** to a corresponding tooth surface **41a** of the first inner helical spline **41** is directed in the second axial direction **X2**. Therefore, the intermediate member **4** is moved in the second axial direction **X2** which is a direction in which the first spring **6** is compressed (refer to FIG. 10). As shown in FIG. 8A, the first inner helical spline **41** is inclined with respect to the crank axis **Ac** (equivalent to the central axis of the intermediate member **4**) so that the intermediate member **4** is able to be moved in the second axial direction **X2** when the positive torque **PT** is transmitted from the crank shaft **1**. The first inner helical spline **41** has a torsion angle **β1**.

FIG. 8B shows a case in which a negative torque **MT** is transmitted from the crank shaft **1** to the supercharger **130** through the gear train **GT**. In this case, an axial component **M1** of an engaging force **M** which is imparted from a tooth surface **31b** of the first outer helical spline **31** to a corresponding tooth surface **41b** of the first inner helical spline **41** is directed in the first axial direction **X1**. Therefore, the intermediate member **4** is moved in the first axial direction **X1** which is a direction in which the second spring **7** is compressed (refer to FIG. 11).

FIG. 9A and FIG. 9B are each an explanatory view for describing functions of the second helical spline coupling

HC2. FIG. 9A shows a case in which the positive torque PT is transmitted from the crank shaft 1 to the supercharger 130 through the gear train GT. In this case, an axial component RM2 of an engaging reaction force RM which is imparted from a corresponding tooth surface 52a of the second inner helical spline 52 to a tooth surface 42a of the second outer helical spline 42 is directed in the second axial direction X2. Therefore, the intermediate member 4 is moved in the second axial direction X2 which is a direction in which the first spring 6 is compressed (refer to FIG. 10). As shown in FIG. 9A, the second outer helical spline 42 is inclined with respect to the crank axis Ac (equivalent to the central axis of the intermediate member 4) so that the intermediate member 4 is moved in the second axial direction X2 when the positive torque PT is transmitted from the crank shaft 1. The second outer helical spline 42 has a torsion angle β_2 . In the present preferred embodiment, the first inner helical spline 41 and the second outer helical spline 42 are inclined in the same direction with respect to the crank axis Ac (equivalent to the central axis of the intermediate member 4). However, the first inner helical spline 41 and the second outer helical spline 42 may be inclined in mutually opposite directions with respect to the crank axis Ac (equivalent to the central axis of the intermediate member 4).

Here, in order that the intermediate member 4 is able to be moved axially, there is provided a relationship shown by the following formula between the torsion angle β_1 of the first inner helical spline 41 and the torsion angle β_2 of the second outer helical spline 42. However, a pitch circle diameter of the first inner helical spline 41 is given as D1, and a pitch circle diameter of the second outer helical spline 42 is given as D2.

$$\pi \times D1 / \tan \beta_1 = \pi \times D2 / \tan \beta_2$$

FIG. 9B shows a case in which a negative torque MT is transmitted from the crank shaft 1 to the supercharger 130 through the gear train GT. In this case, an axial component RM1 of an engaging reaction force RM which is imparted from a corresponding tooth surface 52b of the second inner helical spline 52 to a tooth surface 42b of the second outer helical spline 42 is directed in the first axial direction X1. Therefore, the intermediate member 4 is moved in the first axial direction X1 which is a direction in which the second spring 7 is compressed (refer to FIG. 11).

According to the present preferred embodiment, in the torque fluctuation absorber TFA and also in the vessel propulsion apparatus P1 including the torque fluctuation absorber TFA, the following effects are obtained. That is, as shown in FIG. 7, the torque fluctuation absorber TFA includes a first outer helical spline 31, an intermediate member 4, an outer member 5, a first spring 6, and a second spring 7. The first outer helical spline 31 rotates integrally with a torque transmission shaft TT. The intermediate member 4 is ring-shaped, coaxially surrounds the torque transmission shaft TT, and is able to move in a first axial direction X1 and in a second axial direction X2 which is an opposite direction to the first axial direction X1. The intermediate member 4 includes on an inner circumference 4b thereof a first inner helical spline 41 which is engaged with the first outer helical spline 31 to provide a first helical spline coupling HC1 and includes on an outer circumference 4a thereof a second outer helical spline 42. The outer member 5 is ring-shaped, coaxially surrounds the torque transmission shaft TT, and is regulated in axial movement with respect to the torque transmission shaft TT. The outer member 5 includes on an outer circumference 5a thereof a tooth which meshes with a corresponding gear of a gear train GT. The

outer member 5 includes on an inner circumference 5b thereof a second inner helical spline 52 which is engaged with the second outer helical spline 42 to provide a second helical spline coupling HC2. The first spring 6 biases the intermediate member 4 in the first axial direction X1. The second spring 7 biases the intermediate member 4 in the second axial direction X2.

According to this structural arrangement, the intermediate member 4 coaxially surrounds the crank shaft 1 which is an example of the torque transmission shaft TT. The intermediate member 4 is able to move in the first axial direction X1 and in the second axial direction X2. The intermediate member 4 is linked with the crank shaft 1 through the first helical spline coupling HC1 and linked with the outer member 5 through the second helical spline coupling HC2. When a torque fluctuation occurs in a torque transmission path, due to actions of the first helical spline coupling HC1 and the second helical spline coupling HC2, the intermediate member 4 is moved in the second axial direction X2 in resistance to the first spring 6. It is also moved in the first axial direction X1 in resistance to the second spring 7. Therefore, it is possible to absorb a bidirectional torque fluctuation.

The torque fluctuation absorber TFA further includes a ring-shaped inner member 3 which coaxially surrounds a crank shaft 1 (torque transmission shaft TT). The inner member 3 is regulated in axial movement with respect to the crank shaft 1 and also rotates integrally with the crank shaft 1. The first outer helical spline 31 provides the first helical spline coupling HC1 provided on an outer circumference 3a of the inner member 3. The torque fluctuation absorber TFA may have a higher versatility by using the inner member 3.

The torque fluctuation absorber TFA also includes a ring-shaped base 2 which coaxially surrounds the crank shaft 1 (torque transmission shaft TT) and is fixed to the crank shaft 1. On an outer circumference 2a of the base 2, the inner member 3 is held so as to rotate integrally in a state of being regulated in axial movement. The torque fluctuation absorber TFA further includes a first supporting member 8 and a second supporting member 9. The first supporting member 8 includes an annular linkage portion 8a which is linked with the base 2 in a state of being regulated in axial movement with respect to the base 2 and an annular extension portion 8b which extends outward in a radial direction from the linkage portion 8a. The second supporting member 9 includes an annular linkage portion 9a which is linked with the base 2 in a state of being regulated in axial movement with respect to the base 2 and an annular extension portion 9b which extends outward in a radial direction from the linkage portion 9a. The first supporting member 8 and the second supporting member 9 regulate an axial movement of the outer member 5 between their respective extension portions 8b, 9b. The first spring 6 is interposed between the extension portion 8b of the first supporting member 8 and the intermediate member 4. The second spring 7 is interposed between the extension portion 9b of the second supporting member 9 and the intermediate member 4.

According to this structural arrangement, the inner member 3 rotates integrally with respect to the base 2 fixed to the crank shaft 1 and also regulated in axial movement. The linkage portion 8a of the first supporting member 8 and the linkage portion 9a of the second supporting member 9 are linked with the base 2 and also regulated in axial movement with respect to the base 2. Therefore, the first supporting member 8 and the second supporting member 9 are regulated in axial movement with respect to the base 2. The outer member 5 is regulated in axial movement between the

extension portion **8b** of the first supporting member **8** and the extension portion **9b** of the second supporting member **9**. When a torque fluctuation occurs in the torque transmission path, due to actions of the first helical spline coupling **HC1** and the second helical spline coupling **HC2**, the intermediate member **4** interposed between the outer member **5** and the inner member **3** is moved in the first axial direction **X1** or in the second axial direction **X2**. When the intermediate member **4** is moved in the second axial direction **X2**, the first spring **6** is compressed between the extension portion **8b** of the first supporting member **8** and the intermediate member **4**. When the intermediate member **4** is moved in the first axial direction **X1**, the second spring **7** is compressed between the extension portion **9b** of the second supporting member **9** and the intermediate member **4**. Therefore, it is possible to absorb a bidirectional torque fluctuation.

Further, the outer member **5** is supported so as to rotate coaxially with the crank shaft **1** by the extension portion **8b** of the first supporting member **8** and the extension portion **9b** of the second supporting member **9**. Although not shown, the outer member **5** may be supported so as to rotate coaxially with the crank shaft **1** by only one of the extension portion **8b** of the first supporting member **8** and the extension portion **9b** of the second supporting member **9**.

Further, the extension portion **8b** of the first supporting member **8** supports an inner circumference **5b** of the outer member **5** so as to rotate coaxially with the crank shaft **1**. The extension portion **9b** of the second supporting member **9** supports an outer circumference **5a** of the outer member **5** so as to rotate coaxially with the crank shaft **1**. According to this structural arrangement, it is possible to support each of the outer circumference **5a** and the inner circumference **5b** of the outer member **5** so as to rotate by the extension portion **8b**, **9b** of a corresponding supporting member **8, 9**. Although not shown, the extension portion **8b** of the first supporting member **8** may support the outer circumference **5a** of the outer member **5** so as to rotate coaxially with the crank shaft **1**, and the extension portion **9b** of the second supporting member **9** may support the inner circumference **5b** of the outer member **5** so as to rotate coaxially with the crank shaft **1**.

It is also possible to support the intermediate member **4** so as to rotate coaxially with the crank shaft **1** (torque transmission shaft **TT**) by the extension portion **8b** of the first supporting member **8** and the extension portion **9b** of the second supporting member **9**. Although not shown, the intermediate member **4** may be supported so as to rotate coaxially with the crank shaft **1** (torque transmission shaft **TT**) by only one of the extension portion **8b** of the first supporting member **8** and the extension portion **9b** of the second supporting member **9**.

Further, one of the first supporting member **8** and the second supporting member **9** (the first supporting member **8** in the present preferred embodiment) is integral with the base **2** as a single member. The other of the first supporting member **8** and the second supporting member **9** (the second supporting member **9** in the present preferred embodiment) is fitted onto the outer circumference **2a** of the base **2** and supported in a state of being regulated in axial movement with respect to the base **2**. According to this structural arrangement, one of the first supporting member **8** and the second supporting member **9** is integral with the base **2** as a single member. It is, therefore, possible to make the structure simple. The second supporting member **9** may be integral with the base **2** as a single member, and the first supporting member **8** may be fitted onto the outer circumference **2a** of

the base **2** and supported in a state of being regulated in axial movement with respect to the base **2**.

Further, due to being surrounded by the base **2**, the outer member **5**, the first supporting member **8**, and the second supporting member **9**, a housing space **SS** is provided in which the inner member **3**, the intermediate member **4**, the first spring **6**, and the second spring **7** are housed. According to this structural arrangement, it is possible to house the inner member **3**, the intermediate member **4**, the first spring **6**, and the second spring **7** in the housing space **SS** which is defined by the base **2**, the outer member **5**, the first supporting member **8**, and the second supporting member **9**.

Further, a sub-assembly **SA** (refer to FIG. 6A) is provided which includes the base **2**, the inner member **3**, the intermediate member **4**, the outer member **5**, the first spring **6**, and the second spring **7**. According to this structural arrangement, the sub-assembly **SA** is able to be assembled in advance. The sub-assembly **SA** is able to be incorporated in the crank shaft **1** (torque transmission shaft **TT**). It is, therefore, possible to improve ease of assembly.

Further, the first spring **6** and the second spring **7** have a different spring constant from each other. According to this structural arrangement, depending on a direction in which the intermediate member **4** moves upon occurrence of a torque fluctuation, a spring load to resist the movement of the intermediate member **4** is different.

Further, the first spring **6** has a larger spring constant than the second spring **7**. According to this structural arrangement, it is possible to increase a spring load of the first spring **6** to resist a movement of the intermediate member **4** in the second axial direction **X2** than a spring load of the second spring **7** to resist a movement of the intermediate member **4** in the first axial direction **X1**.

Further, the first spring **6** includes a disc spring, and the second spring **7** includes a helical compression spring. According to this structural arrangement, the disc spring as the first spring **6** has a progressively increasing spring constant in relation to a flexing displacement. Therefore, a high spring load is obtained in resistance to movement of the intermediate member **4** in the second axial direction **X2**. It is possible to enhance the effect of absorbing a torque fluctuation.

Further, when a positive torque **PT** is transmitted from the crank shaft **1** to the supercharger **130**, the intermediate member **4** is moved in the second axial direction **X2** which is a direction in which the first spring **6** is compressed (refer to FIG. 10). In order to realize the above, the first inner helical spline **41** (refer to FIG. 8A) and the second outer helical spline **42** (refer to FIG. 8B) are inclined with respect to the crank axis **Ac** (the central axis of the intermediate member **4**). According to this structural arrangement, when the positive torque is transmitted from the crank shaft **1** to the supercharger **130**, the intermediate member **4** is moved in the second axial direction **X2** which is a direction in which the first spring **6** having a higher spring constant is compressed. Therefore, a torque fluctuation is effectively absorbed. At least one of the first inner helical spline **41** and the second outer helical spline **42** may be inclined with respect to the crank axis **Ac** (the central axis of the intermediate member **4**).

FIG. 12 shows a preferred modified example. The preferred modified example of FIG. 12 is mainly different from the preferred embodiment of FIG. 7 in the following. In the extension portion **8b** of the first supporting member **8**, an annular housing recessed portion **8m** to house the first spring **6** is provided on the other end surface **8d**. The intermediate member **4** includes on the one end surface **4c** the annular

raised portion **4j** which is fitted into the annular housing recessed portion **8m** of the first supporting member **8** so as to slide thereon. This modified example also provides the same effects as those of the preferred embodiment of FIG. 7.

FIG. 13 is a cross-sectional view which shows another preferred modified example of the torque fluctuation absorber TFA. The torque fluctuation absorber TFA of the preferred modified example in FIG. 13 is mainly different from the torque fluctuation absorber TFA of the preferred embodiment in FIG. 7 in that the torque fluctuation absorber TFA includes the oil path **L** that supplies oil to the housing space **SS**. The engine **120** includes a cylinder body **160**, a crankcase **170**, an oil pan **180**, an oil pump **190**, and a suction pipe **200**. The cylinder body **160** is located below a cylinder cover which is not shown. The crankcase **170** is located below the cylinder body **160**. The oil pan **180** is schematically shown and disposed below the crankcase **170**. The oil pump **190** suctions oil stored in the oil pan **180** through the suction pipe **200** and supplies it to each part of the engine **120**. The crankcase **170** houses the crank shaft **1** together with the cylinder body **160**. The crank shaft **1** is rotatably supported by the cylinder body **160** and the crankcase **170**. A journal bearing **300** which rotatably supports a supported portion **1d** of the crank shaft **1** is located at an abutting portion of the cylinder body **160** against the crankcase **170**. The journal bearing **300** provides a bearing clearance **301** between the supported portion **1d** of the crank shaft **1** and a bearing surface of the journal bearing **300**.

The crankcase **170** includes an oil path **171** which extends in an up/down direction. One end **172** (upper end) of the oil path **171** is communicatively connected to the bearing clearance **301**. The other end of the oil path **171** (not shown) is connected to the oil pump **190** through an oil path (not shown). Oil is fed under pressure and supplied from the oil pump **190** through the oil path **171** to the bearing clearance **301** of the journal bearing **300**.

The crank shaft **1** includes a screw hole **1e** and at least one oil path **L1** extending in a radial direction. The fixing screw **12** is screwed into the screw hole **1e**. An oil path **L2** is provided in the screw hole **1e** between the tip of the fixing screw **12** and the bottom of the screw hole **1e**. The oil path **L1** communicatively connects the bearing clearance **301** of the journal bearing **300** with the oil path **L2** at the bottom of the screw hole **1e**.

The fixing screw **12** is, for example, a bolt and includes a head **12a** and a shank **12b**. The shank **12b** includes an under-head portion **12c**, a screw shank **12d**, an oil path **L3** extending in an axial direction, and an oil path **L4** extending in a radial direction. The under-head portion **12c** is adjacent to the head **12a**. The screw shank **12d** extends from a position adjacent to the under-head portion **12c** to a tip **12e** of the shank **12b**. The screw shank **12d** is screwed and fitted into the screw hole **1e** of the crank shaft **1**. An outer circumference **12f** of the under-head portion **12c** is provided by a cylindrical surface which is free of threads. An outer diameter of the outer circumference **12f** of the under-head portion **12c** is smaller than an inner diameter of the screw hole **1e** of the crank shaft **1**. A portion of an inner circumference of the screw hole **1e** which surrounds the under-head portion **12c** may be defined by a cylindrical surface which is free of internal threads. A tubular oil path **L5** is provided between the outer circumference **12f** of the under-head portion **12c** and the inner circumference of the screw hole **1e** of the crank shaft **1**.

In the fixing screw **12**, the oil path **L3** in an axial direction is defined by an axial direction hole which extends from the tip **12e** of the shank **12b** up to a midway portion of the

under-head portion **12c** in the axial direction. The oil path **L3** includes one end **L3a** and the other end **L3b**. The one end **L3a** of the oil path **L3** is communicatively connected with the oil path **L2**. The oil path **L4** extending in a radial direction is defined by a radial direction hole which communicatively connects the other end **L3b** of the oil path **L3** in an axial direction with the tubular oil path **L5**.

At least one oil path **L6** extending in a radial direction is provided between the end surface **1c** of the crank shaft **1** and the inner circumference flange **2f** of the base **2**. The oil path **L6** is defined by, for example, a radial direction groove that is provided on the end surface **1c** of the crank shaft **1**. A tubular oil path **L7** is provided between the inner circumference **2b** of the base **2** and the outer circumference **1a** in a tip portion of the crank shaft **1**. The base **2** defines at least one oil path **L8** which communicatively connects the tubular oil path **L7** with the housing space **SS**. The oil path **L8** is defined by a radial direction hole which penetrates through the outer circumference **2a** and the inner circumference **2b** of the base **2**.

Oil which has been supplied from the oil pump **190** to the bearing clearance **301** of the journal bearing **300** is supplied to the oil path **L1** of the crank shaft **1**. The oil which has been supplied to the oil path **L1** is supplied to the housing space **SS** through the oil path **L2**, the oil path **L3**, the oil path **L4**, the oil path **L5**, the oil path **L6**, the oil path **L7** and the oil path **L8**. One preferred example of the oil path **L** which supplies oil to the housing space **SS** includes the oil path **L1**, the oil path **L2**, the oil path **L3**, the oil path **L4**, the oil path **L5**, the oil path **L6**, the oil path **L7**, and the oil path **L8**.

At least one oil path **L9** is provided between the other end **3d** of the inner member **3** and the other end surface **9d** of the second supporting member **9**. The oil path **L9** is defined by a groove extending in a radial direction which is located at least in one of the other end **3d** of the inner member **3** and the other end surface **9d** of the second supporting member **9**. A tubular oil path **L10** which surrounds the inner member **3** along the outer circumference **3a** of the inner member **3** is provided outside the inner member **3** in a radial direction. The oil path **L9** communicatively connects the oil path **L8** with the oil path **L10** located outside the inner member **3** in a radial direction.

Inside the housing recessed portion **4e** of the intermediate member **4**, a housing space **S1** which houses the first spring **6** is defined by the annular raised portion **8g** of the first supporting member **8**. An oil path **L11** is provided in the annular raised portion **8g** of the first supporting member **8**. The oil path **L11** communicatively connects the oil path **L10** located outside the inner member **3** in a radial direction with the housing space **S1**. The oil path **L11** is defined by a through hole **8n** which penetrates through the annular raised portion **8g**. One end of the through hole **8n** is open at the inner circumference **8j** of the annular raised portion **8g**. The other end of the through hole **8n** is open at the top portion **8k** of the annular raised portion **8g**. Inside the housing space **SS**, oil is supplied from the oil path **L10** located outside the inner member **3** in a radial direction through the oil path **L11** to the housing space **S1** in which the first spring **6** is housed.

A housing space **S2** to house the second spring **7** is provided inside the annular recessed portion **9h** of the second supporting member **9**. The oil path **L10** located outside the inner member **3** in a radial direction is communicatively connected with the housing space **S2**. Inside the housing space **SS**, oil is supplied from the oil path **L10** located outside the inner member **3** in a radial direction to the housing space **S2** that houses the second spring **7**. The second supporting member **9** provides an oil path **L12** which

communicatively connects the housing space S2 with the outside of the housing space SS. The oil path L12 is defined by a through hole which is open at the one end surface 9c of the second supporting member 9 and at the bottom of the annular recessed portion 9h.

According to this structural arrangement, the torque fluctuation absorber TFA includes the oil path L which supplies oil to the housing space SS. Therefore, each sliding portion of the torque fluctuation absorber TFA is lubricated and also cooled by the oil supplied to the housing space SS. When the intermediate member 4 is moved by a torque fluctuation in the first axial direction X1 and in the second axial direction X2, sliding of the first spring 6 with respect to an inner surface of the housing space S1 is lubricated. Sliding of the second spring 7 with respect to an inner surface of the housing space S2 is also lubricated. Further, sliding of the intermediate member 4 with respect to each of the first supporting member 8, the second supporting member 9, the inner member 3, and the outer member 5 is lubricated. Oil supplied to the housing space SS is discharged outside the housing space SS through a clearance provided between the first supporting member 8 and the outer member 5 (refer to the hollow arrow A1). The oil supplied to the housing space SS is discharged outside the housing space SS through a clearance provided between the second supporting member 9 and the outer member 5 (refer to the hollow arrow A2).

Further, a decrease in viscosity of the oil supplied to the housing space S1 that houses the first spring 6 improves a damping effect to absorb a torque fluctuation. A decrease in viscosity of the oil supplied to the housing space S2 that houses the second spring 7 improves a damping effect to absorb a torque fluctuation.

FIG. 14 shows an auxiliary machine-equipped engine 120H as a preferred embodiment of the present invention. The auxiliary machine-equipped engine 120H includes an engine 120 including a crank shaft 1 and an auxiliary machine HK including an input shaft (not shown). A preferred example of the auxiliary machine HK may be a supercharger or may be an alternator. The auxiliary machine-equipped engine 120H further includes a gear train GT which includes a plurality of gears to transmit a driving force from the crank shaft 1 to the auxiliary machine HK and a torque fluctuation absorber TFA which absorbs a fluctuation in torque transmitted to the gear train GT. The torque fluctuation absorber TFA includes a first outer helical spline 31, an intermediate member 4, an outer member 5, a first spring 6, and a second spring 7. The first outer helical spline 31 rotates integrally with a torque transmission shaft TT which includes at least one of the crank shaft 1, the input shaft, and an intermediate shaft (not shown) which is located in a torque transmission path from the crank shaft 1 to the input shaft. The intermediate member 4 is ring-shaped, coaxially surrounds the torque transmission shaft TT, and is able to move in a first axial direction X1 and in a second axial direction X2 which is an opposite direction to the first axial direction X1. The intermediate member 4 has on an inner circumference 4b a first inner helical spline 41 which is engaged with the first outer helical spline 31 to provide a first helical spline coupling HC1 and has a second outer helical spline 42 on an outer circumference 4a. The outer member 5 is ring-shaped, coaxially surrounds the torque transmission shaft TT, and is regulated in axial movement with respect to the torque transmission shaft TT. The outer member 5 includes teeth on an outer circumference 5a thereof. The teeth mesh with corresponding gears of the gear train GT. The outer member 5 includes a second inner helical spline 52 on an inner circumference 5b thereof. The second

inner helical spline 52 is engaged with a second outer helical spline 42 to provide a second helical spline coupling HC2. The first spring 6 biases the intermediate member 4 in the first axial direction X1. The second spring 7 biases the intermediate member 4 in the second axial direction X2.

According to this structural arrangement, the intermediate member 4 is linked with the torque transmission shaft TT through the first helical spline coupling HC1 and linked with the outer member 5 through the second helical spline coupling HC2. When a torque fluctuation occurs in the torque transmission path, due to actions of the first helical spline coupling HC1 and the second helical spline coupling HC2, the intermediate member 4 is moved in the second axial direction X2 in resistance to the first spring 6 or moved in the first axial direction X1 in resistance to the second spring 7. Therefore, it is possible to absorb a bidirectional torque fluctuation in the auxiliary machine-equipped engine 120H.

In the preferred examples so far described, although not shown, the first outer helical spline may be located on the outer circumference 2a of the base 2 or may be located on the outer circumference of the torque transmission shaft TT. Further, the torque fluctuation absorber TFA may be provided around at least one torque transmission shaft TT. Further, the first spring 6 and the second spring 7 may have an equal spring constant to each other, or the first spring 6 may have a smaller spring constant than the second spring 7. Further, the oil path L in the preferred modified example of FIG. 13 may be applied to the preferred modified example of FIG. 12 or the preferred embodiment of FIG. 14.

In the above-described preferred embodiments, an example which includes a jet pump is cited as the vessel propulsion apparatus. However, preferred embodiments of the present invention are applicable to other modes of vessel propulsion apparatuses such as outboard motors, inboard/outboard motors (stern drive, inboard motor/outboard drive), inboard motors, etc. Various features so far described may be used in combination whenever appropriate.

While preferred embodiments of the present invention have been described above, it is to be understood that variations and modifications will be apparent to those skilled in the art without departing from the scope and spirit of the present invention. The scope of the present invention, therefore, is to be determined solely by the following claims.

What is claimed is:

1. A vessel propulsion apparatus comprising:
an engine including a crank shaft;
a supercharger including an input shaft;
a gear train including a plurality of gears to transmit a driving force from the crank shaft to the supercharger;
and
a torque fluctuation absorber to absorb a fluctuation in torque transmitted to the gear train, the torque fluctuation absorber including:
a first outer helical spline rotatable integrally with a torque transmission shaft that includes at least one of the crank shaft, the input shaft, and an intermediate shaft located in a torque transmission path from the crank shaft to the input shaft;
an intermediate member that coaxially surrounds the torque transmission shaft and is able to move in a first axial direction and in a second axial direction opposite to the first axial direction, the intermediate member including a first inner helical spline on an inner circumference thereof and a second outer helical spline on an outer circumference thereof, the first

inner helical spline being engaged with the first outer helical spline to provide a first helical spline coupling; an outer member that coaxially surrounds the torque transmission shaft and is regulated in axial movement with respect to the torque transmission shaft, the outer member including teeth on an outer circumference thereof and a second inner helical spline on an inner circumference thereof, the teeth being meshed with corresponding gears of the gear train and the second inner helical spline being engaged with the second outer helical spline to provide a second helical spline coupling; a first spring to bias the intermediate member in the first axial direction; and a second spring to bias the intermediate member in the second axial direction.

2. The vessel propulsion apparatus according to claim 1, further comprising:

an inner member that coaxially surrounds the torque transmission shaft and is regulated in axial movement with respect to the torque transmission shaft and is rotatable integrally with the torque transmission shaft; wherein the first outer helical spline is provided on an outer circumference of the inner member.

3. The vessel propulsion apparatus according to claim 2, wherein the torque fluctuation absorber further includes:

a base that coaxially surrounds the torque transmission shaft and is fixed to the torque transmission shaft, and on an outer circumference of which the inner member is held so as to be rotatable integrally while being regulated in axial movement; and

a first support and a second support each of which includes an annular linkage that is linked with the base while being regulated in axial movement with respect to the base and an annular extension that extends outward in a radial direction from the annular linkage, the first support and the second support regulating an axial movement of the outer member between the respective annular extensions;

the first spring is interposed between the annular extension of the first support and the intermediate member; and

the second spring is interposed between the annular extension of the second support and the intermediate member.

4. The vessel propulsion apparatus according to claim 3, wherein at least one of the annular extension of the first support and the annular extension of the second support supports the outer member so as to be rotatable coaxially with the torque transmission shaft. 50

5. The vessel propulsion apparatus according to claim 3, wherein one of the annular extension of the first support and the annular extension of the second support supports the outer circumference of the outer member so as to be rotatable coaxially with the torque transmission shaft; and

the other of the annular extension of the first support and the annular extension of the second support supports the inner circumference of the outer member so as to be rotatable coaxially with the torque transmission shaft. 60

6. The vessel propulsion apparatus according to claim 3, wherein at least one of the annular extension of the first support and the annular extension of the second support supports the intermediate member so as to be rotatable coaxially with the torque transmission shaft. 65

7. The vessel propulsion apparatus according to claim 3, wherein

one of the first support and the second support is unitary and integral with the base; and

the other of the first support and the second support is fitted onto the outer circumference of the base and supported while being regulated in axial movement with respect to the base.

8. The vessel propulsion apparatus according to claim 3, 10 wherein

the torque fluctuation absorber further includes a housing which houses the inner member, the intermediate member, the first spring, and the second spring; and the housing is defined by the base, the outer member, the first support, and the second support.

9. The vessel propulsion apparatus according to claim 3, wherein the torque fluctuation absorber further includes a sub-assembly which includes the base, the inner member, the intermediate member, the outer member, the first spring, and the second spring. 20

10. The vessel propulsion apparatus according to claim 1, wherein the first spring and the second spring have different spring constants from each other.

11. The vessel propulsion apparatus according to claim 25 10, wherein the first spring has a larger spring constant than the second spring.

12. The vessel propulsion apparatus according to claim 11, wherein the first spring includes a disc spring, and the second spring includes a helical compression spring.

13. The vessel propulsion apparatus according to claim 30 11, wherein at least one of the first inner helical spline and the second outer helical spline is inclined with respect to a central axis of the intermediate member so that the intermediate member is moved in the second axial direction which is a direction in which the first spring is compressed when a positive torque is transmitted from the crank shaft to the supercharger.

14. A vessel comprising:

the vessel propulsion apparatus according to claim 1.

15. An auxiliary machine-equipped engine comprising:

an engine including a crank shaft;

an auxiliary machine including an input shaft;

a gear train including a plurality of gears to transmit a driving force from the crank shaft to the auxiliary machine; and

a torque fluctuation absorber to absorb a fluctuation in torque transmitted to the gear train, the torque fluctuation absorber including:

a first outer helical spline rotatable integrally with a torque transmission shaft that includes at least one of the crank shaft, the input shaft, and an intermediate shaft located in a torque transmission path from the crank shaft to the input shaft;

an intermediate member that coaxially surrounds the torque transmission shaft and is able to move in a first axial direction and in a second axial direction opposite to the first axial direction, the intermediate member including a first inner helical spline on an inner circumference thereof and a second outer helical spline on an outer circumference thereof, the first inner helical spline being engaged with the first outer helical spline to provide a first helical spline coupling;

an outer member that coaxially surrounds the torque transmission shaft and is regulated in axial movement with respect to the torque transmission shaft, the outer member including teeth on an outer cir-

25

cumference thereof and a second inner helical spline on an inner circumference thereof, the teeth being meshed with corresponding gears of the gear train, the second inner helical spline being engaged with the second outer helical spline to provide a second helical spline coupling;

a first spring to bias the intermediate member in the first axial direction; and

a second spring to bias the intermediate member in the second axial direction.

16. A torque fluctuation absorber to absorb a fluctuation in torque transmitted to a gear train including a plurality of gears, the torque fluctuation absorber comprising:

a first outer helical spline rotatable integrally with a torque transmission shaft;

an intermediate member that coaxially surrounds the torque transmission shaft and is able to move in a first axial direction and in a second axial direction opposite to the first axial direction, the intermediate member including a first inner helical spline on an inner cir-

5

10

15

26

cumference thereof and a second outer helical spline on an outer circumference thereof, the first inner helical spline being engaged with the first outer helical spline to provide a first helical spline coupling;

an outer member that coaxially surrounds the torque transmission shaft and is regulated in axial movement with respect to the torque transmission shaft, the outer member including teeth on an outer circumference thereof and a second inner helical spline on an inner circumference thereof, the teeth being meshed with corresponding gears of the gear train, the second inner helical spline being engaged with the second outer helical spline to provide a second helical spline coupling;

a first spring to bias the intermediate member in the first axial direction; and

a second spring to bias the intermediate member in the second axial direction.
